UNITED STATES PATENT OFFICE.

EDWIN C. WASHBURN, OF MINNEAPOLIS, MINNESOTA.

DUMPING-CAR.

No. 901,270.

Specification of Letters Patent.

Patented Oct. 13, 1908.

Application filed August 19, 1907. Serial No. 389,197.

To all whom it may concern:

Be it known that I, EDWIN C. WASHBURN, a citizen of the United States, residing at Minneapolis, in the county of Hennepin and 5 State of Minnesota, have invented certain new and useful Improvements in Dumping-Cars; and I do hereby declare the following to be a full, clear, and exact description of the invention, such as will enable others 10 skilled in the art to which it appertains to make and use the same.

My invention relates to dumping cars and especially to those having boxes or bodies mounted for lateral pivotal movements so 15 as to dump the load at either side of the car.

The invention is particularly directed to improved means for locking the pivoted box or body of the car in normal position and for releasing the same, and for moving the 20 sides of such box or body to and from operative position.

Generally stated, the invention consists of the novel devices and combinations of devices hereinafter described and defined in 25 the claims.

In the accompanying drawings which illustrate the invention, like characters indicate like parts throughout the several views.

Referring to the drawings, Figure 1 is a 30 plan view of the improved car. Fig. 2 is a side elevation of the same, with some parts broken away and some parts sectioned. Fig. 3 is an end elevation of the car, with some parts sectioned; and Fig. 4 is an end elevation of the car showing the box or body thereof in a dumping position.

The car truck, which may be of any suitable construction, is preferably provided with flanged wheels adapted to run upon 40 rails (not shown). As illustrated in the drawings, the truck frame is made up of side sills 1, center sills or draft sills 2 and cast bolster end sills 3, and the wheels 4 are secured to axles 5 journaled in suitable boxes 45 6 held by brackets 7 rigidly secured to and projecting below the side sills 1. The cast bolster end sills 3 are provided with raised centrally located bosses 3* that project between, are secured to, and serve to space 50 apart the center or draft sills 2. The coupler draft bar *a* is connected to the center sills 2 by a suitable draft rigging *b*, indicated in outline only in Fig. 2. The intermediate portion of the coupler draft bar *a* rests directly upon the raised boss 3* of the adjacent sill 3. The cast truck bolster or end 55

sills 3, it will be noted, is provided with laterally projecting reinforcing flanges, or, in other words, is angular in cross section, being, as shown, channel-shaped. The box 60 or body 8 of the car is pivotally connected to the center sills 2 by heavy hinge brackets 9 and 10, rigidly secured, respectively, to the end portions of said box and sills. As shown, the hinge brackets 9 and 10 are pivotally connected by hinge bolts 11. The car box 8 is thus pivotally supported midway between its sides for pivotal dumping movements in either of two directions transversely of the truck. The sides or doors 12 70 of the box 8 are separable or removable therefrom, and at the upper edges of their end portions they are pivotally connected to the upper members 13 of telescopically extensible legs, the lower sections 14 of which are pivotally connected at their lower ends to bearings 15 rigidly secured to the ends of the transoms 3. As shown, the leg sections 14 telescope into the leg sections 13, and the latter work freely between the adjacent ends 80 of the box and guide bars 16 secured to but spaced apart from the ends of said box, as best shown in Fig. 1. The upper leg sections 13 are connected to the adjacent ends of the box 8, preferably by short chains 17, 85 the purpose of which will hereinafter more clearly appear.

The relative arrangement of the extensible legs, the box and the connections 17 above described is such that when the box stands in 90 a horizontal or normal position, as best shown in Fig. 3, both of the box sides or doors 12 will by gravity be moved into closed positions. To positively lock the said sides to the box when they are thus brought to their closed positions, coöperating lock pins 18 and 95 sockets 19 are provided, and these, as shown, are secured respectively in the opposite edges of the ends of the box 8 and on the end portions of the said sides 12. As clearly shown in Fig. 3, these interlocking parts 18 and 19 are engaged so that they positively lock the sides 12 in closed positions against the sides of the box 8.

To the ends of the box 8 at diagonally opposite sides of the center of the box, I apply locking devices, preferably in the form of pivotally connected dogs 20, the laterally bent free ends of which are adapted to be passed through perforations 21 in the adjacent upper leg sections 13 and into the lock notches 22 formed in the coöperating 100 105 110 115

lower leg sections 14. These locks might be applied to all four of the legs, but it is sufficient to apply them as above stated. When the lock dogs 20 are engaged with the co-operating leg sections as just above stated and as shown in Fig. 3, it is evident that the box 8 is locked in its normal position and the box sides or doors 12 are held against vertical movements and, hence, locked to the box by the co-operating lock pins 18 and sockets 19. The lock dogs 20 are shown as provided with projecting perforated ears 20^a to which tripping connections, such as ropes or wires, (not shown) may be attached and 15 extended therefrom to convenient position for tripping at the side of the car.

When the loaded box is to be turned into a dumping position, the two lock dogs 20 must be moved into released positions so that 20 the box is then free to move with respect to the extensible legs. When the box is released it may, by slight force, be caused to move pivotally toward either side of the truck, or if the box be loaded a little heavier 25 on one side than the other it will itself be moved by gravity into a position to dump the load on that side of the car. By reference to Fig. 4 it will be seen that when the box moves into a dumping position the upper 30 leg sections on the rising side of the box are caused to move telescopically on the co-operating leg sections, thereby increasing the length of these leg sections without causing the connected box side 12 to move from its 35 closed position. The extensible leg sections on the falling or lowered side of the box not being capable of shortening up, serve to lift the box side 12 on the lowered side of the box from normal position and away from 40 the box, so that the load is left free to slide out of the box at one side of the truck. When the box is moved back to its normal position, the dogs 20 automatically reengage with the lock seats in the sections of the co-operating extensible legs, under the action of 45 gravity, so that the box becomes automatically locked upon reaching its normal position. The lifted box side 12 is held by gravity in an approximately vertical position and the connections 17 between the legs and the box are so arranged that under upward movement of the lowered side of the box the sockets 19 on the raised side will be carried into engagement with the co-operating lock pins 18 on the box.

It is important to note that when the box or body is in a dumping position, as shown in Fig. 4, the lowered side of said body is relieved from the weight of the opened door, 60 while the closed door and parts of the extensible legs are added to the raised side of the body or box, so that the said body would be automatically returned to normal position by gravity as soon as the load is dumped.

65 All parts of the truck frame are prefer-

ably constructed of metal. The sides and ends of the box are also preferably constructed of metal suitably reinforced by angle irons, and the bottom of the said box may be either of metal or wood. The box 70 sides 12 are shown as provided at their ends with flanged reinforcing bars 12^a, the upper ends of which are pivotally connected to the upper ends of the co-operating upper leg sections 13 by pins 25. Also in this preferred construction, the lock sockets 19 are shown as formed integral with the said bars 12^a, while the lock pins 18 are shown as directly secured to flanged reinforcing bars 8^a applied to the corners of the box 8. 80

The structural iron side sills 1 of the car truck are cut away above the journal-box, as indicated by dotted lines marked 1^a on Fig. 2, and are reinforced by flanges 7^a of the brackets or pedestal castings 7. 85

By reference to Fig. 3 it will be noted that the bottom 8^a of the car body 8 is located above the lower marginal portions of said box, so that a portion of said box may move below the tops of the wheels, as shown in 90 Fig. 4, when the box is in a dumping position. The said car body 8, at its ends, is provided with angle ends sills 8^b (see particularly Fig. 2) that carry the body, side and intermediate sills 8^c on their lower legs or 95 flanges.

A dumping car of the kind described is capable of many uses, but is especially adapted for use in handling dirt and coal, in which use it will usually be arranged to 100 run upon a track.

What I claim is:

1. The combination with a truck and a box centrally hinged thereto for lateral dumping movements, said box having displaceable sides, of extensible legs pivotally connected to the frame of said truck and to said displaceable sides, and means for locking said box to one or more of the sections of said extensible legs, substantially as described. 105

2. The combination with a truck and a box centrally hinged thereto for lateral dumping movements, said box having displaceable sides, of oppositely disposed extensible legs having their lower sections pivoted to the frame of said truck and having their upper sections connected to the adjacent displaceable sides of said box, and means for locking said box against movement with respect to said lower leg sections and the co-operating leg sections against movement with respect to each other, substantially as described. 115

3. The combination with a truck and a box centrally hinged thereto for lateral dumping movements, said box having displaceable sides and interlocking devices for securing said sides in closed positions when said box is in normal position, of telescopic 125

- leg sections connecting the frame of said truck to said displaceable sides and arranged to lift the same from operative positions, and lock devices on said box engageable with lock seats in the coöperating sections of certain of the said telescopic legs to lock said box in normal position and the said leg sections against telescopic movement, substantially as described.
- 10 4. A car having a rocking body provided with a movable door, and a telescopic direct connection between said door and the frame of the truck arranged to hold said door away from the load, substantially as described.
- 15 5. A car having a rocking body provided with side doors and telescopic door actuating legs directly connected thereto and arranged to hold said doors away from the load in the dumping action, substantially as described.
- 20 6. A car having a rocking body provided with side doors, and telescopic legs directly connected thereto and arranged to hold said doors away from the load in the dumping action, substantially as described.
- 25 7. A car having a rocking body and displaceable doors, in combination with a leg pivoted to and serving to open the door on the lowered side of said rocking body, and for adding the weight of the other door to the raised side of said body, whereby the said box will be arighted by gravity, substantially as described.
8. A car having a rocking body with movable side doors, and door extensible legs pivoted to said doors whereby the weight of the opened door is supported by the truck frame, and the weight of the other door is carried by said body, substantially as described.
- 40 9. A car having a rocking body, extensible door supports, and means for locking said body to said supports, substantially as described.
10. A dump car having truck side sills, cast bolster end sills, and door anchor lugs cast on and carried by said bolster end sills.

In testimony whereof I affix my signature in presence of two witnesses.

EDWIN C. WASHBURN.
